UNITED STATES PATENT OFFICE.

JOSEPH M. STERN AND EMIL M. ELDER, OF CLEVELAND, OHIO.

INTERMENT MAT.

Application filed January 26, 1925. Serial No. 4,954.

Our invention relates to an improvement in a decorative mat for interment purposes, our object being to provide a durable mat which is particularly constructed to closely 5 simulate natural grass; which may be used repeatedly in lining graves and covering newly excavated earth; which will withstand rough wear and usage out doors under all conditions of weather and retain a natural 10 and attractive appearance; and with which the act or ceremony of depositing a dead body in the earth may be deprived of much of its fear, dread and abhorrence.

In the accompanying drawings, Fig. 1 is 15 a perspective view, partly in section, of a grave with a pile of newly excavated earth deposited at one side thereof and a coffin supported in a lowering position above the grave, and showing the sides and top border 20 of the grave and also the pile of earth completely covered by a number of mats of our invention.

Fig. 2 is a top view of a single mat, and 25 Fig. 3 a bottom view thereof. Fig. 4 is a sectional view, enlarged, of a corner piece of the mat.

To mitigate or lessen the grief and natural repulsion of feeling of the mourners during burial proceedings we have conceived the 30 idea of completely concealing all evidences of freshly turned earth around a grave by utilizing a plural number of rectangular mats A, B and C, each having a grass-like material 2 affixed to one side of a pliable body 35 3 of woven material, such as heavy burlap or canvas, the border portions or corners of the woven body being provided with a series of metal grommets or eyelets 4 adapted to receive metal nails or wooden pegs 5. These 40 pegs are driven into the earth to hold the mats in fixed position wherever placed or suspended. Thus, the side walls of earth of grave G are concealed from view by lining them with a mat A approximately four feet 45 wide by twenty-two feet long, the upper edge of the mat having grommets at spaced intervals to permit pegs 5 to be driven into the earth walls near the top of the grave, thereby suspending the mat evenly at all points 50 within the grave closely against the earth walls. In many instances where the earth is loose, wet or of a nature apt to collapse, it is customary to brace the side walls and to cover the earth with wooden planks D, and 55 in that case the lining mat A effectually conceals all the bracing parts and implements.

The earth bordering the grave and the planks, if any, are covered with separate pieces or strips of mats B of any desirable width and length, and these are fastened down by pegs also. The excavated earth is usually piled at one side of the grave, and this mound is completely covered with a large mat C which may be nine feet wide and twelve feet long or any other desirable size. 60 When the grave and surrounding earth surface are covered in this way the entire area matches the natural grass adjoining, and this matching effect is obtained by constructing the mat specifically as follows: Thus, long 70 strips of raffia, a fiber obtained from the leaf-stalks of the raffia palm of Madagascar, are cut into short pieces of substantially equal length and laid parallelly in profusion in a straight row upon one side of woven body 2 75 from edge to edge thereof and then sewed in a straight line at the middle of the row transversely of the fiber pieces. A second row of raffia pieces is then sewed similarly parallelly adjacent the first row with one edge 80 or the ends of the pieces overlapping and intermingling with the fibers of the first row. A large number of such rows of short pieces of raffia are thus sewed to the woven goods 85 2 successively in close formation, the sewed seams 6 extending parallelly at spaced intervals of the goods and the raffia fibers being closely intermingled and more or less matted together like lawn grass. The woven goods and the raffia itself are then colored 90 a brilliant grass green and treated with a glycerin solution to give the fibers a glossy appearance corresponding to the finish found in natural grass and imparting to the fibres the property of readily shedding water and 95 also the quality of permitting the fibers to be easily washed and cleaned after being trampled on and covered with dirt. In this connection it should be understood that an article of this kind is used outdoors in all 100 kinds of weather and is laid frequently upon wet earth or mud and is exposed to severe and trying conditions in use. The fibers and woven material are also treated with a fire-proofing substance, otherwise the matted fibres would quickly ignite and spread flames rapidly during use of the mat or when stored. In brief, after the mat is treated its top portion is grass green and resembles grass so closely that it can not be 105 readily identified as an artificial product; it is durable as the fibers are tough and strong; 110

it is resistant to water and fire; and may be readily washed and cleaned and used repeatedly for interment purposes in all kinds of weather.

5 What we claim, is:

1. An interment mat for lining graves and covering earth, comprising a woven textile body having short pieces of raffia fiber sewed in closely intermingled relation upon one 10 side thereof, said fiber being colored grass green and having a glossy surface and water shedding properties, and both the textile body and the fiber being treated with a fire-proofing substance.
- 15 2. A decorative grave mat of the character stated, comprising a textile fabric base, parallel and contiguous rows of blades of grass arranged on said base, of substantially uni-

form lengths of glass blades parallel to each other and extending transversely of the rows 20 and with the edges of the several rows substantially contiguous to each other, rows of stitches passing through said blades of grass and said textile fabric base longitudinally and substantially centrally of each of said 25 rows of grass transversely of the blades thereof, and a thin film of waterproofing material enveloping each blade of grass whereby a fadeless mat is produced which is impervious to the elements and which will retain the natural appearance of grass.

In testimony whereof we affix our signatures.

JOSEPH M. STERN.
EMIL M. ELDER.
